EXPANSIBLE WATCH BAND OR SIMILAR ARTICLE

Kurt Speck, Palisades Park, N. J., assignor to Jacques Kreisler Manufacturing Corporation, North Bergen, N. J., a corporation of New Jersey

Application February 25, 1950, Serial No. 8,143

Term of patent 3½ years

(Cl. D45—4)

To all whom it may concern:

Be it known that I, Kurt Speck, a citizen of the United States of America and a resident of Palisades Park, in the county of Bergen and State of New Jersey, have invented a new, original, and ornamental Design for Expansible Watch Band or Similar Article, of which the following is a specification, reference being had to the accompanying drawing, forming a part hereof:

Figure 1 is a top plan view of an expansible watch band embodying my new design, the links shown in full lines being repeated across the length of the band as indicated by the dot and dash lines and the conventional end links also being shown in broken lines;

Figure 2 is a bottom edge view of the band as shown in Figure 1 with some of the conventional bottom links indicated in broken lines;

Figure 3 is a top plan view of a portion of the

band illustrating the links in an expanded position; and

Figure 4 is a perspective view of one of the top links.

The dominant feature of my design resides in the elements shown in full lines.

I claim:

The ornamental design for an expansible watch band or similar article, substantially as shown and described.

KURT SPECK.
